(57) **CLAIM**

The ornamental design for a crib curtain, as shown and described.

DESCRIPTION

FIG. 1 is a perspective view showing the front of the crib curtain attached to a baby crib;

FIG. 2 is a rear elevational view of the crib curtain;

FIG. 3 is a front elevational view of the crib curtain;

FIG. 4 is a top plan view of the crib curtain with the ties shown in an alternate position; and,

FIG. 5 is a side view of the crib curtain with the ties shown in an alternate position.

The dotted line just inside the perimeter edge of the crib curtain seen in FIGS. 1 and 3 represents stitching. The broken line showing of the crib in FIG. 1 is for illustrative purposes only and forms no part of the claimed design.
